UNITED STATES PATENT OFFICE.

NOEL PEMBERTON-BILLING, OF LONDON, ENGLAND, ASSIGNOR OF ONE-HALF TO
WORLD RECORD LIMITED, OF LONDON, ENGLAND, A BRITISH COMPANY.

TALKING MACHINE OR LIKE APPARATUS.

Application filed August 15, 1922. Serial No. 582,019.

To all whom it may concern:

Be it known that I, NOEL PEMBERTON-BILLING, subject of the King of England, residing in London, England, have invented 5 certain new and useful Improvements in Talking Machines or like Apparatus, of which the following is a specification.

This invention consists in improvements in or relating to talking-machines of the 10 disc-record type in which uniform speed of the spiral groove of the record in relation to the stylus-point of the recording or reproducing gramophone is desired.

Many suggestions have in the past been 15 made for devices for obtaining the desired speed-relationship between the record-groove and the stylus-point but such earlier attempts do not appear to have met with commercial success. An object of the 20 present invention is to provide improved means for this purpose constructed as an attachment for a gramophone.

According to the chief feature of the present invention means for obtaining uniform 25 speed of the spiral groove of a disc-record in relation to the stylus-point, which means comprise an unitary attachment having a friction-wheel adapted to track with its periphery on or approximately on the spiral 30 of the record-surface and a constant-speed governor geared to said friction-wheel, is characterized by means which are not only driven by an operative connection with the record but in addition are so constructed 35 as to traverse said friction-wheel across the record-surface along a straight line fixed in space and radiating from the center of the record.

The foregoing and other features of the 40 invention will be more clearly understood from the following description, given by way of example, of a preferred embodiment of the invention illustrated in the accompanying drawings, in which—

Figure 1 is a central sectional elevation 45 of a speed-controlling device according to the invention, the section being taken in a plane containing the axis of the sound-box with which the speed-controlling device is associated; and

Figure 2 is a section on the line II—II of Figure 1.

Like reference numerals indicate like parts in both figures of the drawings.

The drawings show mainly diagrammatically one form of the invention in which the speed-controlling mechanism is incorporated with or is formed as an attachment for the sound-box 40. In this example the stylus-point 52 is to be understood as being traversed across a diameter of the record by means of a telescopic tone-arm 38, 39. The sound-box is secured to the outer end of the inner member 39 and the end of the outer member 38 is mounted in a support 37 from which any suitable connection is made to a horn or other sound-projecting device. The turntable is diagrammatically shown at 35 and a disc-record is shown thereon at 36.

The speed-control device comprises a friction-disc 41 mounted in bearings in a dished disc 42 which is secured by a bracket 43, 44 to the tone-arm 39 in close proximity to the sound-box 40. The friction-disc 41 engages with a smaller friction-wheel 45 on the spindle of which is mounted a rotatable brake-carrier 46 located within the rim of the member 42. The brake-carrier is furnished with brake-shoes 47 pressed outwardly by springs 48 the tension of which is controlled by resilient arms 49 pivoted at 50. A slider 51 serves to regulate the outward pressure of the arms 49 and thus to regulate also the tension of the springs 48.

The stylus-point is diagrammatically illustrated at 52 and it will be seen that the latter and the friction-disc 41 both engage the record-surface simultaneously at positions which are close together. Thus, the disc 41 will be rotated by frictional engagement with the record-surface. The speed of rotation of the disc 41 is governed by the pressure of the brake-shoes 47 on the rim 42 and any tendency to increase in speed will be checked by increased pressure of the brake-shoes 47 on the rim 42 brought about by centrifugal force. Stems from the brake-shoes are guided in channels, as clearly 100 illustrated in Figure 2.

It will be therefore seen that as the friction-disc 41 traverses the record-surface by means of its attachment to the telescopic tone-arm 38, 39, it will track on, or approximately on, the spiral record-groove and will travel along a straight line fixed in space and radiating from the center of

rotation of the record-surface; and that part of the record which passes in contact with the disc will be controlled (by reason of the governor control of the disc) to move at an uniform linear speed at all times. As the stylus-point is close to the point of engagement between the wheel 41 and the record-surface it follows that the speed-relation between the stylus-point and the record-groove will also be maintained substantially uniform at all times.

Obviously a recording machine for making records can, according to this invention, be similarly provided with the speed-control mechanisms described and illustrated above.

What I claim as my invention and desire to secure by Letters Patent is:—

1. For a gramophone having a disc record, means for obtaining uniform speed of the spiral track of the record in relation to the stylus point, said means comprising a unitary attachment having in it a friction wheel adapted to track with its periphery substantially on the spiral of the record surface, and a constant speed governor geared to said friction wheel, and, in combination with said attachment, means to move the friction wheel across the record in a straight radial line.

2. For a gramophone having a disc record, means for obtaining uniform speed of the spiral track of the record in relation to the stylus point, said means comprising a unitary attachment having in combination a friction wheel adapted to track with its periphery substantially on the spiral of the record surface and to be driven by that surface, and a constant speed governor secured thereto, and, in combination with said attachment, means operated from the rec-

ord to move the friction wheel across the record in a straight radial line.

3. For a gramophone having a sound-box movable along a straight radial line across a disc record, means for obtaining uniform speed of the spiral of the record in relation to the sound-box stylus, said means comprising a unitary attachment having in combination a driven friction wheel adapted to track with its periphery substantially on the spiral of the record, a constant speed governor geared to said friction wheel and means operative to connect said attachment to the sound-box so that the friction wheel of the attachment is traversed along said radial line with the plane of the friction wheel substantially perpendicular to that line.

4. For a gramophone having a sound-box movable along a straight radial line across a disc record, means for obtaining uniform speed of the spiral of the record in relation to the sound-box stylus, said means comprising a unitary attachment having in combination a driven friction wheel adapted to track with its periphery substantially on the spiral of the record, a constant speed governor geared to said friction wheel and means for mounting said attachment on a tone-arm to which the sound-box is attached so that the plane of the friction wheel is parallel with that of the sound-box diaphragm and the point of contact between the friction wheel and the record surface and that between the stylus point and the record surface are situated close together on the aforesaid straight radial line.

In testimony whereof I affix my signature.

NOEL PEMBERTON-BILLING.
